SIGN LETTER

John B. McMath, Dallas, Tex.

Application January 12, 1948, Serial No. 1,784

5 Claims. (Cl. 40—136)

1

This invention relates to new and useful improvements in sign letters and methods for producing the same.

One object of the invention is to provide an improved metal, fabricated letter particularly adapted to be coated with a glaze or vitreous material.

Another object of the invention is to provide an improved method of fabricating and coating a sign letter wherein sharp bending of the sheet metal is avoided.

An important object of the invention is to provide a method and letter, whereby electric spot welding may be applied to join the parts and the welds substantially concealed; such a method and letter avoiding edge welds and providing smoother edge joints.

A further object of the invention is to provide an improved method and letter which while including welding of the parts does not depend solely upon such welding to hold the parts in their related positions.

Still another object of the invention is to provide a method and letter, whereby the raw edges of the sheets or strips are more adequately covered and protected and water leaks to the interior of the letter, are materially reduced.

A still further object of the invention is to provide an improved method and letter, whereby expansion, shifting or distortion of the elements, during a high temperature coating, may be compensated without rendering the letter commercially objectionable.

Another object of the invention is to provide an improved method and letter, whereby the letter is reinforced and is less likely to distort or lose its desired configuration, although sufficient thermal expansion and shifting is provided to compensate the reaction of the sheet metal when subjected to relatively high temperatures.

A construction designed to carry out the invention will be hereinafter described together with other features of the invention.

The invention will be more readily understood from a reading of the following specification and by reference to the accompanying drawing, wherein examples of the invention are shown, and wherein:

Fig. 1 is a perspective view of a block letter with the lower extremities in transverse section, made in accordance with the invention and prior to coating,

Fig. 2 is an enlarged, transverse, sectional view through one of the sections or members of the uncoated letter, and

Fig. 3 is a view, similar to Fig. 2, of a slightly modified letter.

2

By way of explanation and illustration of the invention, the letter R has been chosen with the understanding that the invention is applicable to all letters, numerals and other block structures or shapes fabricated of sheet metal and generally coated with a finishing material, such as porcelain enamel or other vitreous or siliceous compositions, usually applied by baking or firing.

In the drawing, the numeral 10 designates a block letter which is preferably formed of sheet metal. In general, each letter or shape includes, upright or vertical side walls 11, a bottom 12 and a countersunk or inset face or stroke piece or strip 13, each of which members or elements may be made in one or more pieces, according to the contours or configurations which are involved.

Usually the face strip 13 is made of a single piece of flat sheet metal, properly cut or shaped to establish the desired contour or configuration and the bottom 12 is made likewise, except of greater width and length. The side walls 11 are formed of one or more metal strips and where two or more strips are employed, their upright ends are abutted or joined so as to form continuous side walls. Since the side wall structure is the same, whether short or long or curved, a description of any one member will suffice for all.

Each side wall section, a section being any one of the members, such as the loop A or the leg B, comprises an upright metal strip 14 having an inturned lateral or horizontal flange 15 along its bottom edge and a raw upper edge 16. The flanges 15 of opposite walls overlie the bottom 12, which latter has its outer edges terminating flush with the outer faces of the side walls and is secured to said flanges by bolts 17 or other fastenings.

The face strip is supported and secured by upright hanger strips 18, hanging flat against the upper inner faces of the side strips 14. Each hanger strip has a laterally directed flange 19 along its lower edge, such flanges being directed inwardly of the letter section and supporting the face strip 13, which has its longitudinal edges abutting or adjacent the hanger strips. The upper longitudinal edge portion of the hanger strip is bent or folded to form a longitudinal hanger 20, which has an inverted U-shape in cross-section, so as to hook on or snugly receive the upper edge 16 of the side strip 14.

The metal of the hanger is folded so that the space in the hanger is substantially the same in width as the strip 14, whereby a relatively tight fit of the strip in the hanger is had. This structure assures an efficient joint and at the same time avoids bending the sheet metal upon itself and creating a bend score or a relatively sharp

edge along the longitudinal top of the hanger, as well as not weakening the structure to the extent that would occur with a sharp bend. Further, the longitudinal top of the hanger being comparatively wider and more gradually curved, a better foundation for the coating, will be provided.

In order to fasten the parts in position, spot welding is employed. Spot welds are applied at the points indicated by the numerals 21 and 22, respectively. It will be observed that these welds are not applied at the edges of any of the strips or parts. The welds 21 are between the flat bottom of the face strip 13 and the flanges 19, while the welds 22 are between the flat medial portion of each hanger strip 18 and the side strip 14. The welds are spaced longitudinal of the correlated parts.

From the foregoing it is obvious that when the letter is subjected to baking or firing heat, of the order of 1300 to 1600° F., thermal expansion may take place and even though some of the welds break loose, the parts would remain in place due to the construction. It would be possible in some instances to omit the welds 22 and depend upon other fasteners or the clamping engagement of the hanger 20 over the edge 16 to hold the parts together.

When the fabrication of the letter is completed, said letter is coated in the usual manner with porcelain enamel or other vitreous or siliceous compositions and then fired or baked. The hanger strip 18 provides a rigid reinforcing along the contours of the letter and makes electric spot welding practical. The flanges 19 provide adequate supports for the face strip 13, which latter is, in no instance, entirely dependent upon the welds to hold it in place. Due to the structure, the welds may be spaced at greater distances than would otherwise be necessary and thus, the number of welds for a given letter is greatly reduced. By placing the welds at points spaced from the edges and between the flat surfaces of strips or pieces, such welds are substantially concealed and do not mar the edges of said strips or pieces.

In Fig. 3, a slightly modified construction is shown and includes an identical bottom 23 and stroke or face strip 24 and similar side walls 25 and hanger strips 26. Inturned flanges 27 are formed along the lower longitudinal edge portion of the side walls 25 so as to overlie the bottom 23, while the hanger strips 26 have similar flanges 28 for supporting the stroke 24. A hanger 29, similar to the hanger 20, is formed on each side wall by bending its upper longitudinal edge portion upon itself. The upper edge portion of the strip 26 engages within the hanger 29. The parts may be welded together in the manner hereinbefore described in connection with similar elements in the other figures of the drawings.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. As a new article of manufacture, a block

letter including, a pair of side walls disposed in spaced relationship each having at least one raw edge, separate hanger strips engaged on the raw edges of the side walls overhanging the inner faces of said walls, inwardly directed flanges along the inner longitudinal portions of the hanger strips, a face piece fitting between the hanger strips and engaging the flanges, spaced fastenings between the face piece and the flanges, and a continuous vitreous coating uniting the hanger strip with the side walls and with the face piece and extending over the walls, the face piece and the hanger strips.

2. As a new article of manufacture, a block letter including, a pair of side walls disposed in spaced relationship, separate hanger strips engaged with the side wall and overhanging the inner faces of said walls, inwardly directed flanges along the inner longitudinal portions of the hanger strips, a face piece fitting between the hanger strips and engaging the flanges, spaced fastenings between the face piece and the flanges and between the hanger strips and the side walls, and a continuous vitreous coating uniting the hanger strip with the side walls and with the face piece and extending over the walls, the face piece and the hanger strips.

3. In a structure of the class described, the combination of, a face piece having opposed raw edges, side wall pieces bounding the raw edges of the face piece and having raw edges, hanger strips hung on the raw edges of the side wall pieces therebetween and having supports for the face piece, whereby said face piece is supported between the hanger strips, the face piece being inset with respect to the raw edges of the side wall pieces, electric spot welds between the face piece and the hanger supports, said welds being spaced from each other and spaced from the edges of the face piece and the strip.

4. A device of the class described including, oppositely spaced side walls each having at least one raw edge, hanger strips each having along one longitudinal margin an inverted U-shaped hanger engaged over the raw edge of one of the side walls, a face strip disposed between the hanger strips inwardly of the hangers thereof, supports for the face strip carried by the hanger strips, spot welds between the face strip and the hanger supports, other spot welds between the hanger strips and the side walls, and a continuous vitreous coating extending over the side walls and the strips.

5. A device as set forth in claim 4, with inwardly directed flanges along the longitudinal edge portions of the side walls opposite their raw edges, and a bottom strip secured to side wall flanges.
